(57) **CLAIM**

The ornamental design for a bottle, as shown and described.

DESCRIPTION

FIG. 1 is a perspective view of a bottle showing our new design;

FIG. 2 is a front elevational view thereof, with the rear view, not shown, being identical;

FIG. 3 is a perspective view of another embodiment of our new design; and,

FIG. 4 is a front elevational view of the embodiment of FIG. 3, with the rear view, not shown, being identical.

1 Claim, 4 Drawing Sheets
